UNITED STATES PATENT OFFICE.

HUGH PURDY, OF BELFAST, IRELAND.

WINDOW.

1,323,910.

Specification of Letters Patent. Patented Dec. 2, 1919.

Application filed April 4, 1918. Serial No. 226,696.

To all whom it may concern:

Be it known that I, HUGH PURDY, a subject of the King of Great Britain and Ireland, residing at Belfast, Ireland, have invented certain new and useful Improvements Relating to Windows, of which the following is a specification.

This invention relates to windows of the class having a sliding sash adapted to open inward and its object is to provide an improved window of this class which will be perfectly weather proof when closed while it will also be capable of being opened inward when required.

Under my invention, in order to give a finished appearance to the window, a sliding head is provided in connection therewith to fill in the top of the sash when in the closed position, the head having beveled end surfaces and being so arranged that, when the sash is raised, it is easily moved upward therewith so as to allow of the sash opening inward and when the sash is closed and lowered on to the rabbet of the frame bottom, the sliding head drops down again and closes up the opening which would otherwise be left above the sash top.

The sliding stile may be raised by direct lift, or by lever action, or otherwise, and by any suitable device or devices.

The invention can be applied to single or double sashes.

In order that the invention may be clearly understood I have hereunto appended explanatory drawings showing the invention applied to a single inwardly opening sash.

Figures 1 to 4 show a wooden sash.

Figs. 1 and 1^a show the four corners of the window in front elevation.

Fig. 2 is a cross sectional view on the line 2—2, Fig. 1^a.

Fig. 2^a is a view showing the window raised for ventilation purposes.

Fig. 3 is a sectional plan view on the line 3—3, Figs. 1 and 1^a.

Fig. 4 is a small view showing the whole window in front elevation.

Figs. 5 to 8 show a metal sash.

Figs. 5 and 5^a show the four corners of the window in front elevation.

Fig. 6 is a cross sectional view on the line 6—6, Fig. 5^a.

Fig. 7 is a sectional plan view on the line 7—7, Figs. 5 and 5^a.

Fig. 8 is a small view showing a whole window in front elevation.

The construction of the window is essentially the same in both the examples shown and in the description hereinafter set forth the reference letters used may refer to either 60 the wooden window sash (Figs. 1 to 4) or the metal window sash (Figs. 5 to 8).

Referring to the drawings:

a is the window frame, *b* the outer casing and *c* the inner casing. *d* is the jamb lining. 65 The opening sash *f* of the window is hinged to the sliding stile *g* by means of hinges *i* and the sliding stile in Figs. 1 to 4, has projections *g*¹ and *g*², or equivalent, engaging in corresponding grooves in the sash frame 70 and inner casing *c* so as to exclude wind and rain, while in the modification shown at Figs. 5 to 8 the sliding stile *g* has projections *g*³ and *g*⁴ engaging in corresponding grooves in the outer casing and inner casing 75 respectively. A rabbet joint is also formed between the bottom *f*¹ of the sash *f* and the sill *a*¹ of the window frame. The sides and top of the sash *f* are protected by the outer casing boards *b* and at the opening side of 80 the sash I provide (in the case of the wooden sash) a bead or projection *f*² engaging in a groove *c*¹ in the inner casing *c*.

Above the sash *f* I provide a space *l* with sloped surfaces *l*¹ and *l*² at the ends thereof 85 and in the space *l* I place a sliding head *m* which fills in the space which would otherwise be left above the sash top when the sash is in the closed position. The sliding head *m* is so beveled at its ends that the sloped 90 surfaces *l*¹ and *l*² coöperate therewith to cause it to slide easily upward when the sash is raised so that when fully raised the sash can open freely inward over the top of the sill *a*¹. When the sash is closed the sliding head *m* drops down again by gravity action. 95

The sliding stile *g* may be raised in any suitable way. In the example shown, Figs. 1 to 4, the stile is raised by providing a rack 100 *n* adapted to coöperate with a toothed lifting lever *o*, which is turnably supported on a pin *o*¹ secured to the jamb lining *d*.

This sash has the advantage of being perfectly secured and at the same time giving 105 ventilation in rooms where it is not suitable to leave the window open.

Having now fully described my invention, what I claim and desire to secure by Letters Patent is:—

In a window structure of the character stated with hinged and sliding sash, a win-

dow frame having inclined surfaces at the top thereof, a sliding head carried in the window frame for filling the space between the top of the sash and the lintel of the window when the sash is lowered, having beveled end surfaces slidable along the correspondingly inclined surfaces on the window frame during the up and down sliding

movements of the sash, substantially as set forth.

In testimony whereof I affix my signature in presence of two witnesses.

HUGH PURDY.

Witnesses:

ANDREW HAMILTON,
JOHN KNOX.
